(57) **CLAIM**

I claim the ornamental design for a hookah, as shown and described.

DESCRIPTION

FIG. 1 is a perspective view of the hookah showing my new design;

FIG. 2 is a right view thereof;

FIG. 3 is a front view thereof;

FIG. 4 is a top view thereof;

FIG. 5 is a bottom view thereof;

FIG. 6 is a left view thereof; and,

FIG. 7 is a rear view thereof.

The broken lines in the figures depict a body support for the hookah that forms no part of the claimed design.
